UNITED STATES PATENT OFFICE.

LUDWIG MAUTNER, RITTER VON MARKHOF, OF VIENNA, AUSTRIA-HUNGARY.

APPARATUS FOR DRYING AND ROASTING MALT, &c.

SPECIFICATION forming part of Letters Patent No. 275,097, dated April 3, 1883.

Application filed February 2, 1883. (No model.)

To all whom it may concern:

Be it known that I, LUDWIG MAUTNER, Ritter von Markhof, a subject of the Emperor of Austria-Hungary, residing at Vienna, in the Province of Nether-Austria, in the Empire of Austria-Hungary, have invented certain new and useful Improvements in Drying and Roasting Malt and other Substances and Apparatus therefor; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

All processes and apparatus employed heretofore for drying malt have the great disadvantage of not furnishing a homogeneous material.

The object of my invention is to provide a new and improved device and method for drying malt, whereby a perfectly uniform product is obtained and the drying and roasting can be regulated at all stages.

Figure 1 is a cross-sectional elevation of one of the drying-drums which I use for drying malt. Fig. 2 is a longitudinal elevation of the same, parts being shown in section. Fig. 3 is a cross-sectional elevation of a drum in which the malt can be dried and roasted. Fig. 4 is a longitudinal elevation of the same, parts being shown in section. Fig. 5 shows a sectional view of a malt-drying house. Fig. 6 is a plan view of the same.

The malt is dried in a building in which the drying-drums *a b c* are arranged, one above the other, on three floors, A, B, and C. The drums are provided with openings for the inlet of the malt, and are constructed of wire-netting or perforated sheet metal stiffened by longitudinal ribs *e* of half-round metal.

The openings or meshes of the drums should be made as large as possible and consistent with retaining the grain in the drums.

The drums are provided with trunnions *i i*, which trunnions rest in bearings *fg*, which are preferably made as dry bearings, which do not require any lubricating material. The bear-

ings *g*, if they are not dry bearings, are placed in the wall *M*, as shown in Figs. 2, 4, and 5, and are lubricated from the compartments *A'*, *B'*, and *C'*, respectively adjoining the compartments *A B C*.

The drums are rotated by means of friction-wheels or cog-wheels mounted on shafts *h*, passing through openings in the walls *M*, which openings must be closed as completely as possible, so that no smell of the lubricating-oil, &c., can pass into the drying-chambers *A B C*. The doors and windows of the chambers *A B C* are also closed as completely as possible, so that the air can only enter into the said chambers through the pipes *k l m*.

The drying process consists of three different steps. In the drum *a* the grain is made air-dry. In the drum *b*, into which it then passes, it receives a preparatory warming, and in the drum *c* the actual drying process is effected, and, if required, the malt can also be roasted in the said drum. The green malt is charged into the drum *a* from the chamber *E* through the chute *a'*, which chamber *E* is located above the chamber *A*, and is used as a drying-chamber. After the malt has been air-dried in the drum *a* it is emptied, and the malt passes through the chute *b'* into the drum *b*, and after it has been further dried in the same passes through the chute *c'* into the drum *c*. The finished product passes through the chute *d* into the chamber *R*, and can be discharged from the chute into bags, cars, &c., or upon an elevator which carries it into a storage-house.

The temperature of the air entering the different compartments must be regulated according to the process to which the malt is successively subjected, and according to the product desired. For instance, in the compartment *A* the temperature should be about 104° Fahrenheit, in the compartment *B* from 104° to 112°, and in the compartment *C* from 152° to 194°. The heating apparatus *S*, supplying the hot air, may be of any suitable construction, and is preferably placed in the room *D* below the chamber *C*. The hot air from the heating apparatus must be mixed with cold air before entering the chamber *C*, and this mixture of hot air and cold air preferably takes place in the room *D*.

The warm air passes through the pipe *m* into the chamber *C*, and then through the previously-warmed malt in the slowly-revolving drum *c*, and passes through the pipe *l* into the chamber *B*. If it is too warm, a quantity of cold air is admitted into the pipe *l* by opening the valve *n*. From the chamber *B* the air, after having passed through and imparted a portion of its heat to the malt in the slowly-revolving drum *b*, passes through the pipe *k* into the chamber *A*. If necessary, cold air is admitted through the valve *o* into the pipe *k* to reduce the temperature. From the chamber *A* the air is drawn off by the exhaust-fan *V*, being caused to pass through the malt in the slowly-revolving drum *a*, whereby the malt in the said drum will receive its preliminary drying. The moist air is forced by the fan *V* into the chimney *W*, or, if desired, can be forced through a pipe, *w*, to any other discharge-flue. The fan must have sufficient power to draw all the required volume of hot and cold air through the chambers *A B C*.

With this method of continuous drying, all loss of heat is avoided, and as the driving of the drums *a b c*, as also all manipulations required during the drying, are effected outside of the drying-chambers *A B C*, all possibility of the entrance of injurious and noxious vapors into the drying-rooms is avoided. The rotation of the drums insures that the whole of the malt contained therein shall be uniformly dried. In order that the air shall be forced to pass through the entire body of the malt, the box *d*, Fig. 1, into which the exhaust-pipes open, has fixed to it pieces of cloth or other pliable material, *q*, which are held against the surface of the drum by chains or bands *r*, surrounding the drum. The drums *a b c* must be arranged at suitable heights above the floor, and so that they may be conveniently manipulated while emptying them.

For the production of malt to be used for the manufacture of beer according to the so-called "Pilsen method," which beer is of a very light color, the simple drying, as described, above is sufficient; but for beers that are to have a darker color the malt must also be roasted.

The burning of the malt, as practiced heretofore, deprives it of many of its qualities which are of the greatest value in brewing, and gives a product which often imparts a burned flavor to the beer. If desired, the malt can be roasted to the required degree in the drum *c* in the room *C*. For this purpose a sheet-metal shield, *t*, of parabolic section, is held to the drum, in the focus of which parabolic shield a heating-pipe, *u*, is located, which is provided with suitable valves for shutting off or regulating the heat. The said heating-pipe can be heated to the required degree, either by means of the heating apparatus *S* or by means of a special heater in the chamber *C'*. The heat radiated from the pipe *u* on the surface of the drum *c*, inclosed between the ends of the shield, will effect the roasting of

the malt as the same is brought between the ends of the shield by the rotation of the drum. The parabolic shield has a slit or opening, *t'*, which establishes a communication between the shield and the box *d*, which box *d* is connected with the exhaust-pipe *l*, leading to the chamber *B* above. In this arrangement the pieces of cloth *q*, or other material, are attached to the edges of the shield *t*, as shown.

It is advantageous to arrange the opening *t'* and the box *d* at the lower side of the shield *t*, in order that any grains of malt that may be drawn through the meshes of the drum by the exhaust will not fall upon the hot heating-pipe *u*, as the burning grain would cause objectionable odors.

As stated, all manipulations to be carried on during the drying and roasting process are effected outside of the tightly-closed chambers *A B C*. Instead of three drums, only two, or more than three, may be employed without departing from the nature of this invention, according to the kind of malt to be produced and the degree of heat at which the drying and roasting is to be effected.

The above-described method of operating and the apparatus can be used with advantage not only for heating malt, but also in all cases where a moist substance is to be dried.

I am aware that it is not new in driers to employ air-chambers, together with a damped air-passage above, behind, and at the sides of the furnace; also, wire-gauze cylinders which revolve in the air-chambers and agitate the grain contents; also, that malt has been passed from the hopper through a gudgeon and worm into the cylinder; also, that a spiral wire channel has been formed within the drying-cylinders; also, that a wire cylinder has been driven by a spring and gearing for the purpose of roasting coffee; also, that a wire-gauze cylinder has been combined with steam-pipes and floats; also, that drums have been made of perforated metal with an internal spiral flange and a perforated tubular shaft, of which the ends are fitted in stationary caps; but

What I do claim as new and of my invention is—

1. The combination, with the furnace and cold-air chamber *D*, the superposed chambers *A B C*, communicating with each other by the pipes *k l* and with chamber *D* by the pipe *m*, the cold-air pipes in chambers *B C* for tempering the heat, the rotary cylinders *a b c*, and the highest chamber *E*, containing a suction-fan, all arranged substantially as shown and described.

2. In a drying or roasting drum, the arrangement of a sheet-metal shield, *t*, of parabolic section, applied thereto at any suitable point, and having at its focus a heating-pipe, *u*, which is heated to such a degree that the heat radiated from the pipe *u* and reflected onto the surface of the drum shall effect the roasting

of the malt lying against the latter, substantially as herein shown and described, and for the purpose set forth.

3. The combination, with a perforated drying or roasting drum, of a metal shield, *t*, provided with a slit or opening, *t'*, a heating pipe, *u*, passing through the same, and the box *d*, connected with the exhaust-pipe, substan-

tially as herein shown and described, and for the purpose set forth.

In testimony whereof I affix my signature in presence of two witnesses.

L. MAUTNER,
Ritter von Markhof.
